Specification for Design.

Patented Apr. 25, 1922.

Application filed December 28, 1921. Serial No. 525,482. Term of patent 7 years.

To all whom it may concern:

Be it known that I, DIGBY W. CHANDLER, Jr., a citizen of the United States, and a resident of the city of New York, borough of Manhattan, in the county and State of New York, have invented a new, original, and ornamental Design for Flags or Banners, of which the following is a specification, reference being had to the accompanying drawing, forming part thereof.

The figure is a plan view of a flag, showing my new design.

My design consists essentially of a flag, the ground of which is divided in equal portions in contrasting colors, namely, orange and blue and bearing a medallion decorated with a conventional representation of a wreath and torch supporting an open book, upon which appear the letters P S N Y.

I claim:

The ornamental design for a flag or banner, as shown and described.

DIGBY WILLIAM CHANDLER, JR.
